CLAIM

The ornamental design for a display screen or portion thereof with graphical user interface, substantially as shown and described.

DESCRIPTION

A portion of the disclosure of this patent document contains material for which a claim for copyright is made. The copyright owner has no objection to the facsimile reproduction by anyone of the patent document or the patent disclosure, as it appears in the US Patent and Trademark Office patent file or records, but reserves all other copyrights whatsoever.

FIG. 1 is a front view of a first embodiment of a display screen or portion thereof with graphical user interface; and, FIG. 2 is a front view of a second embodiment of the display screen or portion thereof with graphical user interface. The outer broken line illustrates the display screen or portion thereof, and the remaining broken lines illustrate portions of the graphical user interface. None of the broken lines form part of the claimed design.
